UNITED STATES PATENT OFFICE

HANS ERNST, OF CINCINNATI, OHIO, ASSIGNOR TO CINCINNATI GRINDERS INCORPORATED, OF CINCINNATI, OHIO, A CORPORATION OF OHIO

GRINDING MACHINERY

Application filed December 4, 1926. Serial No. 152,589.

This invention relates to improvements in grinding machinery and has particular reference to mechanism for use in the grinding of spherical articles such as balls for ball 5 bearings.

The principal object of the present invention is the provision of a novel and improved machine for quantity production of spherical members of extreme accuracy as to size.

10 A further object of the present invention is the provision of an improved multiple machine whereby a plurality of series of articles may be simultaneously ground.

Another object of the invention is the provision of a machine which will automatically 15 operate on a plurality of series of spherical articles to successively reduce the several members in each series to same predetermined size and accurate to a fractional thousandth 20 of an inch, both as to diameter, contour and surface.

Other objects and advantages of the present invention should be readily apparent by reference to the following specification taken 25 in connection with the appended drawings, and it will be understood that I may make any modifications in the specific structural details hereinafter disclosed within the scope of the appended claims without departing 30 from or exceeding the spirit of the invention.

Figure 1 is a plan view of a machine embodying the invention, with portions broken away.

35 Figure 2 is a sectional view taken as on the line 2—2 of Figure 1.

Figure 3 is an enlarged section particularly illustrating the work control mechanism as on the line 3—3 of Figure 1.

40 Figure 4 is a horizontal section as on the line 4—4 of Figure 3.

Figure 5 is a fragmentary view in elevation of the cam driving ratchet.

45 Figure 6 is a plan view of an accentuated control cam, and Figure 7 is a view illustrating the shuttle or feed member in an operative position other than that shown in Figure 3.

In the drawings, the numeral 10 designates 50 the base of the machine having mounted

thereon the main bed or casting 11 formed with a central well or chamber 12 and with the annular chamber 13 adapted to receive the coolant 14. Journalled in the bed 11 is the main drive shaft 15 driven as from belt 16 and having its inner end extended into the well 12 and provided with the gear 17. This gear meshes with gear 18 on the grinding wheel spindle 19 which is journalled in the bed of the machine. This spindle bears on its upper portion the grinding wheel 20 retained in position as by nut 21. A thrust bearing 22 serves to support the weight of the wheel and facilitate free rotation thereof with spindle 19.

55 The wheel itself is formed with a plurality of peripheral grooves 23 substantially corresponding in transverse configuration to the shape to be produced on the work pieces 60

24. The gear 18 in turn meshes with gear 25 on shaft 26 which has a worm 27 meshing with pinion 28 of shaft 29 to operate the latter at a speed possibly one-tenth the R. P. M. of spindle 19. Shaft 29 extends upward 65 through bed 11 and serves to operate the control portions of the machine. These include an inner compound gear member having the large gear portion 30 and the smaller portion 31. This gear is rotatably mounted on 70 bearing flange 32 of the bed casting and is arranged concentric with spindle 19.

75 Circumscribing the spindle 19 is the annular rotary table 33 supported on the bed 11 as by the anti-friction bearings 34. This 80 table has secured thereto the internal gear 35 meshing with the drive pinion 36 on shaft 29, with the result that compound gear 30—31 and table 33 both derive their motion from shaft 29, the table moving slowly in a counter-clockwise direction as respects Figure 1, as is indicated by the arrow thereon,

85 and the compound gear rotating as does the grinding wheel in a clockwise direction, as is indicated by the arrows. The table serves as a moving support for a plurality of work controlling units. These units are ordinarily 90 identical in structure and the description of a single unit should therefore suffice for a complete understanding thereof. One of such 95

units is shown in Figure 3 of the drawings. The table 33 carries the stud 37 on which is rotatably mounted gear 38 driven through gear 39 from the large gear 30. This gear has integral therewith sprocket 40 for a purpose hereinafter described.

10 Stud 37 further serves as a pivotal support for the swinging frame 41 of the work controlling unit, whose weight is further carried by the anti-friction bearings 42 facilitating free in and out oscillatory movement of the unit. Such oscillatory movement is effected through interengagement of roller 42' on frame 41 with the control cam 43 secured to the flange 32 of the bed, this cam plate also serving as a cap to retain the compound gear in position.

The cam itself is shown in detail in Figure 6 of the drawings, from which it will be seen that it is of bi-lateral form providing for ejection of a work piece at each half revolution of the table and for corresponding operations at opposite sides. The cam has the pair of lobes 44 which serve to produce maximum outward swinging movement of the control unit frames against the inward actuating force of the individual control springs 45. In addition, it has a steep drop as at 46 to allow initial inward movement of the control unit to operative or grinding position coupled with a portion of gradual inward lead as at 47 for controlling the gradual reduction in size of the work piece, preferably with a slight concentric portion as at 48, providing for a dwell in movement of the parts for final sizing and then a sharp rise at 49, again swinging the control unit outward into work receiving and ejecting position. That these parts may be best understood, the showing in Figure 6 has been made diagrammatic and accentuated over the actual shape of the cam, as indicated in Figure 1.

The swinging units themselves include the main frame designated as an entirety by the reference character 41 and the supplemental slide 50, adjustable relative to the main frame as by screw 51. Slide 50 has journalled therein shaft 51' for the regulating wheel 52, provided on its lower end with a sprocket 53, driven by chain 54 from sprocket 40 through the gear connections 39-30, as is shown in Figure 1 and at the right of Figure 2.

55 The swinging unit also bears a work rest blade 55, having its face grooved or corrugated as indicated at 56 to interfit with the ribs 57 intermediate the grooves 23 of the grinding wheel. Disposed in opposition to
60 the operative face of work rest 55 is a work steadyng rod 58. The utility of this should be particularly apparent by reference to Figure 3, from which it will be seen that in the form of invention here described, the operative faces of the grinding and regulating

wheels are in a vertical plane, rather than a horizontal plane as has been customary in the past with commercial centerless grinders. As a result the work rest 55 and rod 58 together form a guide trough down which the work pieces move or pass during grinding.

It will be understood that gravity tends to urge the work pieces downward. Consequently, if some means were not provided for controlling the position of the work pieces when the grinding and regulating wheels were separated by the cam lobes 44, the work pieces would tend to rest one upon the other and not be properly engaged within the successive grooves 23. Use is therefore made of the transfer shuttle 59, having a plurality of work receiving notches 60. A rectangular guideway 61 cooperating with the control frame 62 of the shuttle, controls the movement thereof. 85

In operation when the unit 41 is moved outwardly as by cam lobe 44, the chute formed by the members 55-58 will overlie the discharge tube 63, so that the lowermost work piece may drop out of the machine through said chute. At the same time the rotation of table 33 will cause plunger 64 to ride upwardly on actuating cam 65. This plunger has a rack 66 meshing with pinion 67 on shaft 68. Said shaft bears ratchet 69 engaged by pawl 70 on cam 71. 90 95

It will be understood by reference to Figure 3 that rotation of the cam 71 there illustrated in a clockwise direction as actuated by lifting of plunger 64, will first cause a rearward movement of the shuttle withdrawing same from engagement with the work pieces 24 against the tension of the actuating spring 72. Continued rotary movement of the cam by its engagement with frame 62 will then raise the shuttle member a sufficient amount to cause uppermost notch 60 to be raised into alignment with the uppermost groove 23 of the grinding wheel. As the cam continues its rotation, it will still hold the shuttle in raised position, but will release the rearward pressure allowing spring 72 to shift the shuttle forward substantially into engagement with the work pieces held between the grip of the grinding and regulating wheels. In this position the flat side 73 of the cam will be against the side of the frame, while the arcuate surface 74 will be holding the shuttle raised against downward pull of the spring 72. This is the position occupied by the parts prior to the outward swinging movement of the control unit caused by lobe 44. On the outward swinging travelling movement cam 65 actuates plunger 64 sufficiently to impart a quarter rotation to the cam 71, moving the shuttle downward to the position shown in Figure 3. By this downward movement the lowest work piece is released both from retention by the groove in the grinding wheel and retention by the

shuttle with the result that it will fall out through tube 63 and be discharged. At the same time the series of balls previously held by engagement in the grooves 23 of the grinding wheel are still properly held in spaced relation by the fingers of the shuttle and prevented from accidental displacement by being steadied by work rest 55, rod 58 and the surface of the regulating wheel itself. 5 The balls will therefore be shifted downward by the shuttle for proper engagement in the next ensuing groove of the grinding wheel. At the same time a new work piece has been introduced at the top of the column through the aperture 75. The work pieces are normally supplied from a suitable hopper or the like, through a trough or tube 76, carried as by frame 77, rising from bed 11. A suitable unitary work piece 10 delivering mechanism may be employed in conjunction with the discharge tube. The particular form here illustrated, comprises a trigger device 77' having a portion projecting within the tube and a depending portion engageable by trip lug 78 on the swinging unit 41. As the lug passes beneath the trip, a single work piece is released thereby and allowed to drop into groove 79, leading into apertures 75. It will then roll down 15 the groove and through the receiving aperture at the proper moment by gravity. Continued rotation of the table will move unit 41 out of engagement with lobe 44 of the control cam, when the unit will swing inward 20 and the balls be pressed into the grooves of the grinding wheel for joint actuation by the grinding and regulating wheels. At this moment plunger 64 will ride upward on cam 25 80, causing a withdrawal of the shuttle, followed by an upward movement of the shuttle and a subsequent inward movement 30 into ball guiding position. It is then ready for the next shifting of the balls at subsequent separation of the grinding and regulating wheels. The plunger 64 will then ride 35 down on the rear surface 81 but the shuttle will be held in raised position due to contact between flat side 73 of the cam and the frame 40 62. The movement of the plunger will therefore be an idle one which is permitted, due to the pawl and ratchet connection between the cam and plunger. It will thus be seen 45 that a reciprocating movement of the plunger intermittently effected by cam on the bed of the machine, will cause an intermittent constant direction actuation of the cam member on the upward movement of the plunger with an absence of actuation on the rear 50 stroke. Inasmuch as the cam 43 and support 77 for the work are both rigidly carried by the bed, these parts, together with the actuating cam for the individual unit plungers 55 serve jointly to supply fresh work pieces to 60 each unit successively to insure continuous

operation of each unit on a plurality of work pieces.

It will be understood that the grinding wheel is operated at a high or grinding rate of speed as for example, 1200 R. P. M. and in a direction to press the several work pieces against the work rest 55, while the regulating wheel 52 is actuated in the direction of the arrow in Figure 4 or clockwise at a slow rate of speed. Consequently, the grinding wheel 75 performs the function of removal of stock from the work pieces, while the regulating wheel frictionally engages and rotates the work pieces. In order that all parts of the work piece may be properly presented to the grinding wheel for action thereon, the regulating wheel axis is preferably set at a slight angle to the grinding wheel, causing a diagonal thrust to be exerted thereby. This necessitates the regulating wheel being trued 80 to present a straight line of contact with the series of balls parallel with the operative face of the work rest. On account, however, of the tilting of the axis, this means that the actual surface is not cylindrical, but slightly 85 concaved as has been shown in Figure 3 of the drawings. 90

From the foregoing description taken in connection with the accompanying drawings, the general structural features and advantages of the present machine should be readily apparent, and it will be noted that there has been provided a machine for centerless precision grinding of balls or like articles, in which a single contoured grinding wheel 100 serves to simultaneously operate on a plurality of series of independently controlled work pieces and that therefore the one grinding wheel is able to effect maximum production in minimum time. In addition, attention 105 is invited to the fact that by the use of the vertical arrangement, gravity serves to supply the rough work pieces and to insure discharge of the completed articles, while the shuttle mechanism controls their step by step 110 or progressive advance. This progressive advance is particularly desirable since through its use the rough work piece may be presented in the first groove of the grinding wheel and roughed out, the work pieces being successively presented to ensuing grooves, each of which has to remove less and less stock, so that the final groove ordinarily has to perform but little stock removal, therefore, has 115 relatively slight wear and can be depended on 120 to most accurately size the work pieces just prior to their ejection from the machine. 125

I claim:—

1. A centerless grinder, including a grinding wheel, a plurality of regulating wheel units peripherally opposed thereto, said individual units each including a regulating wheel and an associated work support, a single means for sequentially shifting the several units toward and from the grinding 130

wheel, and additional means for individually adjusting the regulating wheels relative to their supporting units to control the size of work produce by such individual units.

5 2. A centerless grinder, including a grinding wheel, a plurality of regulating wheel units peripherally related to the grinding wheel and each including a regulating wheel member and a work support for joint peripheral engagement with a work piece to control the positioned rotation thereof, means for bodily shifting the units circumferentially of the grinding wheel and additional means for imparting an in and out movement to the 15 units during said shifting.

3. A centerless grinder, including a grinding wheel rotatable about a vertical axis, a plurality of regulating wheels peripherally opposed to the periphery of the grinding 20 wheel and providing a plurality of work receiving throats, means for positively controlling the vertical shifting of the work in the individual throats and a single actuator for sequentially energizing said individual work 25 controlling means.

4. A grinding machine, including a rotary grinding wheel and a work controlling unit mounted for swinging movement adjacent the grinding wheel, said unit including a work 30 supporting member and a regulating wheel rotatable in the same direction about its axis as the grinding wheel but at a much reduced rate of speed for frictionally engaging the work to control the rotation thereof, and 35 means for swinging the unit to shift the work into and out of operative engagement with the grinding wheel.

5. A grinding machine, including a rotary grinding wheel and a work controlling unit 40 mounted for swinging movement adjacent the grinding wheel, said unit including a work supporting member for supporting work pieces and a regulating wheel rotatable in the same direction about its axis as the 45 grinding wheel but at a much reduced rate of speed for frictionally engaging the work to control the rotation thereof, and means for swinging the unit to shift the work into and out of operative engagement with the 50 grinding wheel, said means including a controlling cam having a plurality of portions for imparting different degrees of movement to the work supporting member whereby both the initial operative engagement of the work 55 and grinding wheel and the progressive feed determining the amount of stock removal from the work are controlled by the cam.

6. A centerless grinder, including peripherally opposed grinding and regulating members 60 rotatable about distinct vertical axes, a work supporting member disposed in the throat between said grinding and regulating members, and means normally preventing shifting movement of the work during 65 grinding but actuatable for positively advanc-

ing the work along the supporting member.

7. A grinding machine of the character described, including a grinding wheel and an opposed regulating wheel rotatable about upright axes, a work support intermediate 70 said wheels to support work pieces against the thrust of the grinding wheel, means for intermittently engaging the work pieces to advance same along the support, and means on the grinding wheel for positively engaging the work pieces to control the position thereof when disengaged by the work shifting means.

8. A machine for the production of contoured articles, including a grinding wheel 80 having a plurality of work engaging grooves of contour complementary to that to be formed on the work pieces, and a work controlling unit pivotally supported adjacent the periphery of the grinding wheel, said unit including a frame member, a work support carried by the frame member, a regulating wheel movably mounted on the frame member for engagement with work pieces on the support, and means for urging the regulating 90 wheel in the direction of the grinding wheel to force the work pieces thereagainst.

9. A machine of the character described, including a bed, a grinding wheel rotatably supported by the bed, a plurality of work 95 units supported by the bed for holding work pieces and adapted to be operatively associated with the grinding wheel, intermittently operating work shifting mechanism carried by the individual units for moving 100 work pieces step by step transversely of the operative face of the grinding wheel, cam means for imparting an in and out movement to the units between each step as respects the operative face of the grinding wheel, additional cam means for actuating the work shifting devices, and means for imparting relative rotary movement to the cams and parts actuated thereby, whereby the cams will sequentially correspondingly actuate 110 corresponding parts of the several units.

10. A machine of the character described, including a bed, a grinding wheel mounted on the bed for rotation about a vertical axis, said grinding wheel having a plurality of work engaging grooves formed in the surface thereof, a plurality of work supporting units mounted adjacent the periphery of the grinding wheel, work supports carried by the units, regulating wheels carried by the units for engagement with work on the supports, means for sequentially moving the units into and out of operative relation to the grooved face of the grinding wheel, and means on the units disposed in opposition to the work support for imparting a step by step advance to work pieces on the support when the units are swung out of operative relation to the grinding wheel, whereby individual work pieces will be successively presented to the 120 125 130

several grooves on the face of the grinding wheel.

11. A machine of the character described, including a bed, a grinding wheel mounted on the bed for rotation about a vertical axis, said grinding wheel having a plurality of work engaging grooves formed in the surface thereof, a plurality of work supporting units mounted adjacent the periphery of the grinding wheel, work supports carried by the units, regulating wheels carried by the units for engagement with work on the supports, means for sequentially moving the units into and out of operative relation to the grooved face of the grinding wheel, and means on the units disposed in opposition to the work support for imparting a step by step advance to work pieces on the support when the units are swung out of operative relation to the grinding wheel, whereby individual work pieces will be successively presented to the several grooves on the face of the grinding wheel, said work advancing means including an actuating cam movable in a constant direction, a reciprocating plunger, and connections between said parts for intermittently rotating the cam on reciprocation of the plunger.

12. In a machine of the character described, the combination with a peripherally grooved grinding wheel, of a regulating wheel unit movable toward and from the grinding wheel, said unit including, a frame, a regulating wheel carried thereby, a work support carried by the frame adjacent the regulating wheel on the grinding wheel side thereof, a supplemental work guiding member carried by the frame and spaced from the work support for limiting movement of a work piece transversely of the support, and means adjacent the guide for imparting an advancing movement to work pieces along the support.

13. A grinding machine of the character described, including a bed, a spindle vertically mounted in the bed, a grinding wheel carried by the spindle, means for rotating the spindle and wheel at a grinding speed, a table rotatably mounted on the support axial with the spindle, work supporting units mounted on the table for movement therewith and oscillation relative thereto, said units each comprising a work support for peripheral engagement with a rotating work piece and an associate slowly driven regulating wheel for peripheral engagement with the work piece to control the rate of rotation thereof, a control cam carried by the bed and in engagement with the units and consecutively imparting predetermined movement to the several units as they are carried about the cam by rotation of the table, and means for automatically supplying work pieces to the units at predetermined points on the rotation of the table.

14. A grinding machine of the character described, including a bed, a spindle verti-

cally mounted in the bed, a grinding wheel carried by the spindle, means for rotating the spindle and wheel at a grinding speed, a table rotatably mounted on the support axial with the spindle, work supporting units mounted on the table for movement therewith and oscillation relative thereto, a control cam carried by the bed and in engagement with the units and consecutively imparting predetermined movement to the several units as they are carried about the cam by rotation of the table, means for automatically supplying work pieces to the units at predetermined points on the rotation of the table, and additional means on the units for imparting an intermittent advancing movement transversely of the operative face of the grinding wheel to the work pieces as the table is rotated.

15. A grinding machine, including a grinding wheel rotatable about a vertical axis, and a work supporting unit disposed adjacent said grinding wheel, said unit having a work support and a regulating wheel adjacent the support, means for supplying work pieces to the space bounded in part by the regulating wheel and the work support, means for retaining the work pieces within said space, and additional means for positively intermittently advancing the work pieces along the support.

16. A machine of the character described, including a bed, a grinding wheel spindle vertically mounted therein, a grinding wheel carried by the spindle, a table rotatable concentric with the spindle, work supporting units mounted on the table and including individual regulating wheels on the units for peripheral engagement with work pieces during the grinding thereof, means for rotating the spindle, additional means for rotating the table at a different rate, and planetary gear mechanism for imparting rotation to the regulating wheels of the several units at a relatively slow rate of speed to control the rate of rotation of the work pieces engaged thereby.

17. A grinding machine, including a rotary grinding wheel, a work controlling unit pivotally mounted for oscillating movement as an entirety toward and from the grinding wheel to feed work pieces carried thereby into the grinding wheel, said unit including a regulating wheel and an opposed work rest, and means for controlling the position of work pieces relative to and advancing same along the said work rest.

18. A grinding machine including a bed, a rotary grinding wheel mounted thereon, a rotary table mounted on the bed, a work controlling unit pivotally mounted for oscillating movement as an entirety on the table toward and from the grinding wheel, said unit including a regulating wheel, a work rest and means for controlling the position and advance of the work, and cam means fixed

on the bed for oscillating the work controlling unit.

19. A grinding machine including a bed, a rotary grinding wheel mounted thereon, a rotary table mounted on the bed, a work controlling unit for supporting work pieces pivotally mounted on the table for oscillating movement as an entirety toward and from the grinding wheel, resilient means for oscillating the unit toward the grinding wheel to feed the work pieces into the grinding wheel, and positive means for progressively limiting the approach of the unit to the grinding wheel and for oscillating the unit away from the grinding wheel.

20. A grinding machine including a bed, a rotary grinding wheel mounted thereon, a rotary table mounted on the bed, and a work controlling unit pivotally mounted on the table for oscillating movement as an entirety toward and from the grinding wheel, said unit including a regulating wheel and a work rest forming a trough in which the work is adapted to be adjustably positioned for presentation to the grinding wheel.

21. A grinding machine including a bed, a rotary grinding wheel mounted thereon, a rotary table mounted on the bed, a work controlling unit pivotally mounted on the table for oscillating movement as an entirety toward and from the grinding wheel, said unit including a regulating wheel and a work rest forming a trough in which the work is adapted to be adjustably positioned for presentation of the grinding wheel and means for retaining the work in its adjusted position in the trough.

22. A grinding machine, including a rotary grinding wheel, a work controlling unit pivotally mounting for oscillating movement as an entirety toward and from the grinding wheel, said unit including a regulating wheel and an opposed work rest jointly engaging work pieces for presentation to the grinding wheel and additional means for adjusting the regulating wheel relative to the unit.

23. A grinding machine, including a rotary grinding wheel, a work controlling unit pivotally mounted for oscillating movement as an entirety toward and from the grinding wheel, said unit including a regulating wheel and an opposed work rest jointly engaging work pieces for presentation to the grinding wheel, additional means for adjusting the regulating wheel relative to the unit and means for controlling the position of the work relative to the work rest and regulating wheel and for advancing said work along the rest.

24. A grinding machine, including a rotary grinding wheel, a work controlling unit pivotally mounted for oscillating movement as an entirety toward and from the grinding wheel, said unit including a regulating wheel and an opposed work rest jointly en-

gaging work pieces for presentation to the grinding wheel, means for controlling the position of the work relative to the work rest and regulating wheel and for advancing said work along the rest, and cam means carried on the bed for oscillating the work controlling unit to feed the work pieces into the grinding wheel.

25. A grinding machine, including a rotary grinding wheel, a work controlling unit pivotally mounted for oscillating movement as an entirety toward and from the grinding wheel, said unit including a regulating wheel, an opposed work rest, additional means for adjusting the regulating wheel relative to the unit, means for controlling the position and advance of the work, and cam means carried on the bed for oscillating the work controlling unit.

26. A grinding machine including a rotary grinding wheel and a work controlling unit pivotally mounted as an entirety for oscillating movement adjacent the grinding wheel, said unit including a work supporting member and a regulating wheel rotatable in the same direction about its axis as the grinding wheel but at a much reduced rate of speed for frictionally engaging the work to control rotation thereof and means for oscillating the unit to shift the work into and out of operative engagement with the grinding wheel.

27. A grinding machine including a rotary grinding wheel and a work controlling unit pivotally mounted as an entirety for oscillating movement adjacent the grinding wheel, said unit including a work supporting member and a regulating wheel rotatable in the same direction about its axis as the grinding wheel but at a much reduced rate of speed for frictionally engaging the work to control rotation thereof, means for oscillating the unit for shifting the work into and out of operative engagement with the grinding wheel and additional means for adjusting the regulating wheel relative to the unit.

28. A machine for the accurate production of work pieces of circular form in cross section comprising a grinding wheel rotatable at a high grinding rate of speed, a work table rotatable co-axial with the grinding wheel and bearing a plurality of oscillatable units, said units each comprising a regulating wheel for peripheral engagement with a work piece in opposition to the engagement of the grinding wheel therewith and an associated work support adjacent the regulating wheel for taking up the thrust of the grinding wheel on the individual work piece, and a stationary control cam having means consecutively engageable by successive regulating wheel units, said cam having portions for moving the units into non-grinding relation to the grinding wheel and additional portions

for limiting the approach of the individual regulating wheels to the grinding wheel to control the size of work piece produced thereby.

- 5 29. A machine for the accurate production of work pieces of circular form in cross section comprising a grinding wheel rotatable at a high grinding rate of speed, a work table rotatable co-axial with the grinding wheel and bearing a plurality of oscillatable units, said units each comprising a regulating wheel for peripheral engagement with a work piece in opposition to the engagement of the grinding wheel therewith and an associated work support adjacent the regulating wheel for taking up the thrust of the grinding wheel on the individual work pieces, a stationary control cam having means consecutively engageable by successive regulating wheel units said cam having portions for moving the units into non-grinding relation to the grinding wheel and additional portions for limiting the approach of the individual regulating wheels to the grinding wheel to control the size of work piece produced thereby, and means for relatively adjusting the operative relation of individual regulating wheel units to the cam to control the size of work produced by such individual work piece units.
- 10 30. A machine for the accurate production of work pieces of circular form in cross section comprising a grinding wheel rotatable at a high grinding rate of speed, a work table rotatable co-axial with the grinding wheel and bearing a plurality of oscillatable units, said units each comprising a regulating wheel for peripheral engagement with a work piece in opposition to the engagement of the grinding wheel therewith and an associated work support adjacent the regulating wheel for taking up the thrust of the grinding wheel on the individual work pieces, a stationary control cam having means consecutively engageable by successive regulating wheel units said cam having portions for moving the units into non-grinding relation to the grinding wheel and additional portions for limiting the approach of the individual regulating wheels to the grinding wheel to control the size of work piece produced thereby, and means for relatively adjusting the operative relation of individual regulating wheel units to the cam to control the size of work produced by such individual work piece units.
- 15 31. A machine for the accurate production of work pieces of circular form in cross section comprising a grinding wheel rotatable at a high grinding rate of speed, a work table rotatable co-axial with the grinding wheel and bearing a plurality of oscillatable units, said units each comprising a regulating wheel for peripheral engagement with a work piece in opposition to the engagement of the grinding wheel therewith and an associated work support adjacent the regulating wheel for taking up the thrust of the grinding wheel on the individual work pieces, a stationary control cam having means consecutively engageable by successive regulating wheel units said cam having portions for moving the units into non-grinding relation to the grinding wheel and additional portions for limiting the approach of the individual regulating wheels to the grinding wheel to control the size of work piece produced thereby, and means for relatively adjusting the operative relation of individual regulating wheel units to the cam to control the size of work produced by such individual work piece units.
- 20 32. A grinding machine including a rotary grinding wheel, a work controlling unit pivotally mounted adjacent the grinding wheel for oscillating movement toward and from the grinding wheel, the said work controlling unit including a regulating wheel and an opposed work rest jointly engaging work pieces to support same and control their rotation, the adjacent faces of the wheels forming a grinding throat therebetween, means for adjusting the regulating wheel relative to the unit, means for controlling the position of the work pieces relative to the regulating wheel and work rest and for advancing said work pieces along the work rest, and means for effecting the oscillations of the work controlling unit to vary the width of the grinding throat to thereby determine the diameter of the work to be produced.
- 25 33. In a grinding machine the combination of a rotating grinding wheel, a work rotation controlling and supporting unit pivotally mounted for oscillating movement toward and from the grinding wheel and including a work rest member for supporting work pieces and a regulating wheel for controlling the rate of rotation of said work pieces, and cam means for controlling the oscillations of the work controlling unit to determine the rate of feeding of the work pieces into the grinding wheel and the final size thereof.
- 30 34. In testimony whereof I affix my signature. HANS ERNST.

- 35 31. A machine for the accurate production of work pieces of circular form in cross section comprising a grinding wheel rotatable at a high grinding rate of speed, a work table rotatable co-axial with the grinding wheel
